CLAIM

The ornamental design for an all-in-one communication device, as shown and described.

DESCRIPTION

FIG. 1 is a front elevational view of an all-in-one communication device showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front, top and left side perspective view thereof;

FIG. 8 is a rear, bottom and right side perspective view thereof;

FIG. 9 is a front, top and left side perspective view showing the all-in-one communication device with a camera in a closed state; and,

FIG. 10 is an enlarged view of portion 10 in FIG. 7.

The even-dash broken lines in the drawings illustrate portions of the all-in-one communication device which form no part of the claimed design. The dash-dot-dot broken lines represent the extents of the detail view and form no part thereof.
